Primary Examiner—James Gandy*Assistant Examiner*—Stacia Sinuik*Attorney, Agent, or Firm*—Birch, Stewart, Kolasch & Birch,
LLP[57] **CLAIM**

The ornamental design for a windshield wiper frame connector, as shown and described.

DESCRIPTION

FIG. 1 is a perspective view of a windshield wiper frame connector showing my new design;

FIG. 2 is a top plan view thereof;

FIG. 3 is a bottom plan view thereof;

FIG. 4 is a left end elevational view thereof;

FIG. 5 is a right end elevational view thereof; and,

FIG. 6 is a side view of FIG. 1 with the opposite side being a mirror image thereof.
